INSULATING BASE FOR AN ELECTRIC APPLIANCE

Howard A. Smith, St. Louis, Mo., assignor to
Knapp-Monarch Company, St. Louis, Mo., a
corporation of Missouri

Application January 26, 1938, Serial No. 187,007

13 Claims. (Cl. 53—10)

My invention relates to electrical appliances and particularly to a means for supporting them on a table top or other surface. Among the objects of my invention is the provision of a new and improved base for an electrical appliance which is simple in design, efficient in operation and comparatively simple to manufacture.

Another object is the provision of a new and improved insulating base for an electrical appliance wherein one structural part serves the purpose both of a rigid reinforcing member and a supporting means for the base.

Another object is the provision of a supporting base for a low mounted electric appliance which is relatively inexpensive to manufacture and which combines semi-rigid metallic parts and a rigid non-metallic part into a rigid base by securing said parts together with a minimum number of clamping elements.

Still another object is the provision of a solid insulating base for electric appliances consisting of a pair of semi-rigid stampings clamped together upon a rigid non-metallic ring by a means acting solely upon the stampings and completely out of contact with the ring.

A further object is the provision of a base for an electric appliance comprising a wooden plate having an open center and recesses formed on the opposite faces adjacent the open center adapted to the reception of stampings clamped thereon in order to provide rigidity to the assembled base.

A further object is the provision of a wooden ring for a hollow plate for supplying reinforcement and support for a pair of semi-rigid stampings, the wooden ring being built in sections with the grain running parallel to the length of each in order that the direction of the grain will be substantially continuous around the ring in order to provide said ring with a maximum of strength and rigidity.

Still a further object is to provide an insulating base for a low mounted electrical appliance featuring metallic sheets separated by a reinforcing member of low heat conductivity separating the sheets one from another and elevating them above a surface such as a table top in order to provide a series of closed and circulating air spaces for insulating purposes.

Still a further object is to provide an insulating base for a low mounted electric appliance featuring metallic sheets separated by a reinforcing member of low heat conductivity separating the sheets wherein the parts are assembled by a metal to metal contact at only two places remote

from the reinforcing member and the table surface on which the device may be positioned.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of my device with sections broken away to show the construction.

Figure 2 is a front elevation.

Figure 3 is an end elevation.

Figure 4 is an enlarged view of a section taken on the line 4—4 of Figure 1.

Figure 5 is a front view partially in section taken on the line 5—5 of Figure 1 and drawn to a slightly larger scale.

Figure 6 is a bottom view of Figure 5 with portions broken away to show the construction.

Figure 7 is a fragmentary top view of a wooden reinforcing ring.

Figure 8 is an enlarged exploded bottom view of portions of the wooden ring; and

Figure 9 is a view of one of the stampings.

In this embodiment of my invention, the electrical appliance chosen to be supported is a twin waffle iron indicated generally by the numeral 10 shown supported by a base indicated generally by numeral 12. The waffle iron is supported within a pair of casings 13 and 14 upon which rest corresponding tops 15 and 16 therefor, the whole being supported by a series of depressed portions 17, three in number for each casing and formed from the metal comprising said casing, as best seen in Figures 2 and 4.

The supporting base 12 consists of an upper shallow dished part comprising a metallic stamping 18 forming a semi-rigid plate which is provided with raised projections 19 impressed therein coinciding with the depressed portions 17 for supporting the appliance casing. A fluted wooden ring 20 supports the stamping 18 and the ring in turn is supported by a series of downward projecting buttons 21 upon a surface such as a table top 22 or the like. The entire assembly comprises a low mounted electric appliance resting upon a broad substantial base giving the effect of a streamlined modern design.

In order to design such a low mounting having an extreme rigid construction which at the same time provides a suitable insulation against heat from the appliance which would otherwise harm the surface of a table top or the like, an unique construction has been devised providing the re-

quired insulation and at the same time reducing the number of parts and the operations necessary to assemble them to an absolute minimum. The insulating features and the rigid construction incorporate in part the wooden plate 20 forming a rigid ring having an open six sided central portion directly underneath the appliance casings. On the lower face of the ring completely surrounding the central portion is a recess 25 extending an appreciable distance inward from the lower face of the ring. Adapted to fit within the recess 25 is a dished stamping 26 having a six sided shape precisely the same in outline as the recess and provided with flat horizontal edges 27 which fit snugly against the bottoms of said recesses. It is notable that the outline of the stamping 26 coincides with the outline of the recess so that the edges of the stamping will fit snugly against vertical walls 28 of the recesses. On a top face 29 of the ring 20 there is formed a recess or groove 30 which takes the general form of the outline of the ring itself as best seen in Figures 1 and 6.

The upper stamping 18 is provided with a turned down rim or flange 31 having a perimeter which exactly fits the groove 30 at a height sufficient to permit it to rest in the bottom of the groove and support the shallow dished central portion of the stamping in a position elevated slightly above the upper face 29 of the ring. It should be noted also that the upper stamping 18 is dished slightly but not quite so pronouncedly as the lower stamping 26. Here too the perimeter of the upper stamping is almost exactly coincident with the upper groove 30 so that the flanges when inserted within the groove, not only are supported by the bottom of the groove, but also rest snugly against vertical surfaces 32 forming the outside wall of the groove 30. The stampings are dished in order to increase their rigidity and the upper stamping in particular is flanged not only to increase the structural rigidity but also to add to the appearance of the assembled device. Both stampings are held in their positions within the recesses or grooves in the ring by means of a pair of bolts 33 which draw them toward each other against the ring 20. The ring so positioned between the edges of the stamping provides for the formation of a closed air space 34 between the surfaces of the central portions of the stampings. It will become apparent that the only metal to metal contact between the stampings is that supplied by the bolts 33, thus reducing to a minimum the tendency of the base to conduct heat from the appliance casing to the space immediately above the table top, it being borne in mind that the wooden ring 20 has a relatively low heat conductivity.

Details of the construction of the depressed portion 17 and raised projections 19 are shown in Figure 4. The depressed portions have an outwardly bent tongue 35 which is received in a corresponding slot 36 in the raised portion where, in the course of manufacture, the tongue is bent after insertion so that a lip of the tongue overlies the upper flat surface of the projection thus fastening the appliance casing 13 to the upper stamping 18 at these points.

In order to form a firm and rigid base for the appliance, the semi-rigid stampings need be reinforced at the edges with a reinforcing ring of the nature of the wooden ring 20 herein disclosed. It is further important that this ring be of substantial as well as simple construction in order to produce a durable base since the ring

must stand a considerable portion of the strain. In order that it may serve the purpose of a suitable reinforcement and support, the ring is constructed of a plurality of sections including long straight side sections 40 and end sections 41 and 42 curved at the outer edge, all the parts being adapted to form, when assembled, an elongated base for the appliance. Sections 40 are joined to the curved sections 41 by a means of a mortise and tenon joint, the section 40 being supplied with a tenon 43 and curved sections 41 or 42 with a suitable mortise 44. It is important to note that the direction of the wood grain in the curved sections 41 and 42 is lengthwise of the section, and at the junction of these end sections with the side sections the direction of grain makes a blunt angle with the direction of the grain in the straight side section 40 thus in effect carrying the direction of the grain around the corners. Again it is to be noted that the two curved sections 41 and 42 are joined by a short separate tenon 45 receivable into suitable mortises 46 and 47 respectively in the sections 41 and 42. The direction of grain in the wooden tenon 45 is across the short dimension thereof again operable to form, when assembled, an obtuse angle with the direction of grain in the curved sections 41 and 42. It will become apparent that having the wooden ring divided into a plurality of sections with the grain in proper alignment the direction of grain is carried as near as possible around the ring in substantial conformance with its perimeter thus adding greatly to the strength and rigidity of this reinforcing member.

There has been provided then a rigid base of high insulating quality for a low mounted electrical appliance which takes advantage of structural design in that each piece is designed to resists strain in a specified direction, all of which when assembled as a whole cooperate one with another so that suitable bracing action is supplied in all directions. The ring forms a rigid reinforcing plate for supporting the entire device and for strengthening the stampings which in turn are dished to varied depths in order to increase their rigidity and permit them, when assembled together within the recesses of the reinforcing plate, to cooperate therewith in supplying a rigid, solid insulating base which can be held in assembled position by a minimum of securing means.

Some changes may be made in the construction and arrangement of the various parts of my device, without departing from the real spirit and purpose of my invention, and it is my intention to cover by my claims, any modified forms of structure, or use of mechanical equivalents, which may be reasonably included within their scope.

I claim as my invention:

1. In an electric appliance supporting means a pair of independent plate like metallic parts, a relatively thick non-metallic ring of insulating material, means for supporting said ring close to a table top or the like, means at the central portions of the metallic parts remote from the ring and table top cooperable in clamping said parts to opposite sides of the ring in spaced relation to each other, and means for attaching the appliance to one of said parts.

2. In an electric appliance supporting means a pair of separate dished stampings, a relatively thick non-metallic ring of insulating material having means thereon cooperable with the stampings, means for supporting said ring in spaced relation to a table top or the like, means secured

to the central portions of the stampings remote from the ring for clamping said stampings to opposite sides of the ring spaced from each other by said ring and means for attaching one of said stampings to an appliance casing.

3. Supporting means for an electric appliance casing comprising a pair of separate dished stampings, a relatively thick non-metallic ring, one of said stampings having a flange at the 10 edge and reception means on one face of the ring adapted to receive said flange in edgewise contact, another side of said ring being adapted to receive the other of said stampings in flatwise contact and means at the central portions of the 15 stampings remote from the ring for clamping said stampings to the ring in spaced relation to each other.

4. A base for an electric appliance comprising a rigid non-metallic ring having means forming 20 recesses on opposite faces thereof, a pair of dished stampings having the edges thereof receivable respectively in said recesses and securing means remote from the ring for holding said stampings in a rigid assembled position separated by said ring.

25 5. A base for an electric appliance comprising means forming a flat non-metallic reinforcing member of rigid construction having means for supporting it upon the surface of a table or the like, a central open portion and means forming recesses in upper and lower faces of said reinforcing member surrounding the open portion, a lower deeply dished part receivable into the recess of the lower face in inverted position so that the entire part is retained inward from said 30 lower face, an upper shallow dished part having a turned down rim receivable into the recess on the upper face in inverted position so that the part is disposed above said upper face and the innermost surface of the lower part and means 35 attachable to the dished parts only for drawing them against the reinforcing member to a rigid assembled position separated by said member from each other.

40 6. An insulating base for an electric appliance comprising a rigid ring of low heat conductivity having means thereon for supporting it upon the surface of a table top or the like and means forming a recess in the lower face thereof, a stamping receivable into said recess forming the upper wall 45 of a lower circulating air space for insulating purposes, means forming a recess in the upper face and stamping receivable therein forming with the base and the lower stamping a closed air space for insulating purposes, a casing for the appliance supported at a plurality of isolated points 50 on the upper stamping forming a circulating air space therebetween for insulating purposes and means attached to the stampings remote from the rim for securing said stampings and the casing 55 together in position on said ring.

60 7. An insulating base for a low mounted electric appliance comprising a rigid ring of low heat conductivity provided with means for supporting it above the surface of a table or the like, a pair 65 of plate like parts retained in separated position against opposite faces of said ring and an appliance casing of relatively large area mounted on one of said parts at a plurality of isolated points of contact forming with said parts a plurality of 70 insulating air spaces between the casing and said table top.

75 8. An insulating base for a low mounted electric appliance comprising a stamping and a frame of low heat conductivity for supporting said stamping in a position above a table top or the

like to form a first insulating air space, a second stamping securable in spaced relation to the first stamping in a position separated therefrom by said frame forming thereby a second insulating air space and a casing for said appliance secured 5 upon the second stamping in spaced relation thereto forming therebetween a third insulating space.

9. An insulating base for supporting a low mounted electric appliance on a table top or the 10 like comprising a rigid ring of low heat conductivity having a recess in the lower face thereof, a lower separate metallic part receivable in said recess having an elongated upwardly dished portion extending inward from the face and away from 15 the table top, an upper metallic part and means on the ring for accommodating said part in a position separated from the lower part by said ring forming an air space therebetween, and a pair of metallic connecting means attached to the 20 metallic parts one at each end adjacent the side of the dished portion remote from the ring forming a braced mounting for the metallic parts on said ring and the only contacts of relatively high heat conductivity between said parts. 25

10. A base for an electric appliance comprising means forming a flat non-metallic reinforcing member of rigid construction having means for supporting it upon the surface of a table or the like, an open central portion and means forming 30 recesses in the upper and lower faces thereof, a lower relatively deep dished stamping receivable into the lower recess in inverted position, an upper relatively shallow dished stamping receivable into the upper recess in a position separated from 35 the lower part, a casing for the appliance supported at a plurality of separated contact points upon the upper stamping and clamping means attached to said casing above the contact points and to the lower stamping for clamping said casing and both said stampings in position on the reinforcing member. 40

11. A base for an electric appliance comprising means forming a flat non-metallic reinforcing member of rigid construction having upper and 45 lower faces and projections on one for supporting it upon the surface of a table or the like, an open central portion, means forming a walled recess in the lower face surrounding the central portion and means forming a walled recess in the upper 50 face, a lower deeply dished semi-rigid part having a flat edge adapted to be received within the lower recess in position inward from the face so as to be supported by the walls and bottom thereof within the plane of the recess, an upper relatively 55 shallow dished stamping having a flanged rim receivable into the upper recess in a position bearing against the walls and bottom thereof separated by said non-metallic member and an air space together from the other stamping and means attached to said stampings remote from said 60 reinforcing member for holding said stampings in rigid position against said member at the outer edges and the rims thereby bracing the assembled parts against lateral movement by operation of 65 the sides of said recesses.

12. A rigid base for a low mounted electrical appliance comprising a pair of relatively shallow semi-rigid stampings, a rigid reinforcing and separating ring, clamping means attached to the 70 stampings supplying a tensil force operable to force the rims of said stampings in compression against the ring to maintain the parts of said base in rigid vertical assembly, and means forming recesses in the ring for reception of the edges of 75

the stampings so that a tendency of the edge of one to laterally distort the base by pushing against its recess wall is counteracted by contact of the other stamping edge with its respective recess wall in order to supply a bracing sufficient to hold the entire base in rigid permanent assembly.

13. A rigid base for a low mounted electric appliance comprising a pair of rimmed semi-rigid stampings, a rigid reinforcing and separating ring, clamping means for holding the stampings in spaced relation to each other against the ring to

5 maintain the parts of said base in rigid vertical assembly, means forming a polygonal recess in one face of said ring and a polygonal rim on one of said stampings receivable thereinto, means forming a substantially curved recess in the other face of said ring and a correspondingly shaped rim on the other stamping receivable thereinto co-operable with the first recess and stamping to provide rigidity for said base in all lateral directions.

HOWARD A. SMITH.
